UNITED STATES PATENT OFFICE

150,021

DESIGN FOR A FLEXIBLE CHAIN FOR A
BRACELET OR SIMILAR ARTICLE

Virginia A. Mazurk, New York, N. Y.

Application March 4, 1947, Serial No. 137,310

Term of patent 3½ years

(Cl. D45—4)

To all whom it may concern:

Be it known that I, Virginia A. Mazurk, a citizen of the United States, residing at New York, New York, in the county of New York and State of New York, have invented a new, original, and ornamental Design for a Flexible Chain for a Bracelet or Similiar Article, of which the following is a specification, reference being had to the accompanying drawing, forming part thereof.

Fig. 1 is an edge elevational view of a flexible chain showing my new design;

Fig. 2 is a top plan view thereof; and

Fig. 3 is a sectional view taken on the line 3—3 of Fig. 2.

The backs of the links are the same as the fronts.

I claim:

The ornamental design for a flexible chain for a bracelet or similar article, as shown and described.

VIRGINIA A. MAZURK.
